US00D700550S

(12) **United States Design Patent**
Capristo

(10) **Patent No.:** **US D700,550 S**
(45) **Date of Patent:** ** *Mar. 4, 2014

(54) **VEHICLE HOOD**

(71) Applicant: **Capristo Exhaust Systems GmbH**,
Sundern (DE)

(72) Inventor: **Antonio Capristo**, Sundern (DE)

(73) Assignee: **Capristo Exhaust Systems GmbH**,
Sundern (DE)

(*) Notice: This patent is subject to a terminal disclaimer.

(**) Term: **14 Years**

(21) Appl. No.: **29/444,843**

(22) Filed: **Feb. 5, 2013**

(30) **Foreign Application Priority Data**

Oct. 1, 2012 (EM)	002111732
Oct. 17, 2012 (EM)	002120378
Dec. 20, 2012 (EM)	002157495
